CLAIM

The ornamental design for a stand for display device, as shown and described.

DESCRIPTION

1. Stand for display device

1.1 : Perspective

1.2 : Rear perspective

1.3 : Bottom perspective

1.4 : Front

1.5 : Back

1.6 : Left

1.7 : Right

1.8 : Top

1.9 : Bottom

1.10 : Enlarged

1.11 : Exploded

1.12 : Enlarged

1.13 : Reference

1.14 : Enlarged

Reproductions 1.10 and 1.12 are enlarged views of portions of reproduction 1.3 and 1.11, respectively; reproduction 1.11 shows the cover for the cable being opened; reproduction 1.13 shows the state of use with the display device and reproduction 1.14 is an enlarged view of its rear perspective

(Continued)

view; the broken lines indicate portions of the article that form no part of the claimed design.
